UNITED STATES PATENT OFFICE.

FRANK H. SHEPHERD AND EMIL SCHWAB, OF LOWELL, ASSIGNORS TO
JAMES W. TUFTS, OF MEDFORD, MASSACHUSETTS.

DESIGN FOR THE CASING OF A SODA-WATER APPARATUS.

Specification forming part of Design No. **8,018**, dated January 19, 1875; application filed January 6, 1875.
[Term of Patent 14 years.]

To all whom it may concern:

Be it known that we, FRANK H. SHEPHERD and EMIL SCHWAB, of Lowell, in the county of Middlesex and State of Massachusetts, have invented and produced a new and original Design for the Casing of a Soda-Water Apparatus, of which the following is a full, clear, and exact description, reference being had to the accompanying photograph making part of this specification.

This invention consists in an ornamental design for the casing of a soda-water apparatus to be placed against a wall, the operator standing in front of the apparatus.

In the photograph, A represents the lower or main portion of the casing of a soda-water apparatus, which is of rectangular form. The upper portion of the apparatus is provided with a flat top, b, and an inclined portion, c, on each side, extending from the main portion A to the top B, and beyond the inclined portions c project the arched portions d of the front and rear walls of the casing. To the front wall of the casing is secured an ornamental tablet, B, consisting of two end portions, e e, and an intermediate central portion, f. C is a door, which forms the front of the

upper part of the apparatus, and is balanced on hinges secured to it on the inner side, near its center of gravity. This door C is made ornamental, as shown, and is provided in front with a bracket, h, for supporting a statue or other ornament; but, if desired, the bracket may be dispensed with.

What we claim as our invention, and desire to secure by Letters Patent, is—

1. The design for the casing of a soda-water apparatus, consisting of the rectangular portion A, having a flat top, b, and an inclined portion, c, on each side, in combination with the arched portions d of the front and rear walls, substantially as herein shown and described.

2. The design of the balanced door C, substantially as shown and described.

3. The design of the front tablet B, substantially as shown and described.

Witness our hands this 30th day of December, A. D. 1874.

FRANK H. SHEPHERD.
EMIL SCHWAB.

In presence of—

JOHN S. SEARLE,
WM. R. CADY.
